MEANS AND METHOD OF PACKAGING CANDY CANES

Filed April 16, 1928

UNITED STATES PATENT OFFICE

BRASHER O. WESTERFIELD, OF CHICAGO, ILLINOIS, ASSIGNOR TO BUNTE BROTHERS,
OF CHICAGO, ILLINOIS, A CORPORATION OF ILLINOIS

MEANS AND METHOD OF PACKAGING CANDY CANES

Application filed April 16, 1928. Serial No. 270,241.

My invention relates to means for packaging candy, and more particularly to means for packaging candy canes.

In packaging candy canes and the like for shipment, considerable care must be exercised in order to avoid, as far as possible, the breakage thereof in transit. If goods such as candy canes are chipped, marred or disfigured in the slightest degree, said canes are rendered practically unsalable in the hands of a dealer. Because of the inherent brittleness of candy canes, it requires only the slightest impact therewith to effect the defacement thereof and hence in packaging a plurality of candy canes within a container for the purpose of shipment or for stocking the goods, said canes should be separated so as to prevent the contacting of one with another.

Considerable difficulty resulting from the defacement and breakage of candy canes has heretofore been experienced because of the packaging methods which have been employed and one of the primary objects of my invention is to provide methods and means whereby candy canes may be packaged in such a manner that the losses resulting from breakage and the like will be reduced to a minimum.

More specifically, it is an object of my invention to provide improved means for packaging candy canes whereby a simple method of packaging said candy canes may be practiced very economically, said method consisting in nesting a pair of canes with the tip of one positioned within the crook of the other, inserting a resilient or cushion-like filler strip which serves to separate said canes and then inserting said canes within a container, the resilient filler member functioning in this instance to urge external portions of the canes against the sides of the container thereby maintaining the canes snugly fitted and separated within the container.

Another object of my invention is to provide means to enable the practice of an expeditious method of expeditiously packaging candy canes and the like wherein the canes are arranged in nested relation with the tip of one positioned within the crook of the other, a one-piece cushioning element is then

inserted around the tips of both canes and within the crooks thereof and then the canes are inserted within a container, one width of which is substantially equivalent to the diameter of the canes, the other width thereof being such that when the canes are inserted they will be held close enough together to retain the cushion like filler member under compressive strain.

A still further object of my invention is to provide means for packaging candy canes wherein a unitary strip of wax coated material is folded longitudinally and inserted between nested canes, one portion of the folded strip passing around the tip of one cane and the other portion passing around the tip of the other cane, the wax coating upon the strip serving to lend resiliency and to prevent adhesion of the canes with the strip when said canes are snugly fitted within a container.

These and other objects will be more apparent from the following detailed description when considered in connection with the accompanying drawing wherein:

Figure 1 is a perspective view disclosing a folded waxed strip or filler of the type which I employ in practicing my improved method of packaging candy canes.

Figure 2 is a perspective view of a pair of candy canes disclosing the positions occupied by the canes prior to the insertion therebetween of the filler strip shown in Figure 1.

Figure 3 is a perspective view of a pair of nested canes having the resilient filler member inserted therebetween, a container being disclosed in position to receive said canes.

Figure 4 is a plan view of a container into which a pair of canes have been inserted, a portion of the container being broken away to more clearly disclose parts otherwise hidden, and

Figure 5 is a sectional view taken transversely of the container along the line 5—5 of Figure 4.

Referring now to the drawing wherein like numerals have been employed to designate similar parts throughout the various figures, it is to be understood that in practicing my improved method of packaging candy canes I

employ a unitary filler strip 2 which is folded longitudinally, as clearly shown in Figure 1. I prefer to use strip material which has been impregnated or coated with wax or other suitable material, one purpose of this coating or impregnation being to render the strip more resilient or cushion-like and another to prevent adhesion. In Figure 2 I have disclosed a pair of candy canes 4 in nested relation, 5 that is to say with the tip 6 of each cane positioned or nested within the crook 8 of the other. After the canes have been positioned in this manner, I insert the filler strip 2 between the canes as clearly shown in Figure 3. 10 This may be readily accomplished by first bending opposite extremities of the strip 2 as shown by the dotted lines in Figure 1 and after the strip has been formed in this manner it may very easily be inserted or lowered 15 between the canes with opposite extremities of the filler strip or cushioning element passing around the ends and within the crooks of both canes and the central portion of the strip extending between the staffs of the canes. In 20 this connection it will be observed that by having the filler strip impregnated or coated with wax, the possibility of adhesion between the candy canes and the strip is avoided. With the canes arranged in the nested relation 25 disclosed in Figure 3, they are in proper position for insertion within a suitable container or package 10.

One width of this container 10 is substantially equal to the diameter of the canes as 30 shown in Figure 5. As the assembled canes are inserted within the container 10 the walls 12 of the container are adapted to hold the canes close enough together to keep the filler member or strip 2 under compressive strain. 35 Thus the resiliency or cushioning characteristic of the strip 2 functions to maintain portions of the canes in contact with the inner surface of the container walls 12, thereby avoiding any lost motion laterally of the container. 40 The length of the container is such that the ends thereof will snugly cap the crooks 8 of the canes as clearly shown in Figure 4. It will therefore be apparent that the filler strip 2 not only serves as a resilient 45 spreader to effectively separate the candy canes, but also provides a very effective means for limiting lost motion when said canes are packaged, that is, no relative movement is experienced by the canes during the shipping 50 or handling of the container 10. Figure 5 shows how the sides of the filler strip 2 laterally engage the surfaces of the canes and 55 function as cushion-like spreaders.

From the foregoing it will be understood 60 that my invention enables the practice of a very simple and effective method of packaging candy canes and also provides a cane retaining means which reduces to a minimum the breakage or defacement of the canes. 65 The resilient or cushion-like ma-

terial which I employ is very inexpensive and the ease with which said unitary strip may be inserted between a pair of nested canes serves to greatly accelerate the speed with which candy canes may be packed. 70 As hereinbefore suggested, the inherent brittleness of candy canes renders the same very susceptible to marring or breakage and my invention serves to effectively counteract these difficulties. It is also to be understood that my invention is not limited to the use of the particular type of filler strip described, but contemplates the use of many other modifications which possess similar qualities of resiliency and economy of construction which 75 will similarly present a cushion-like effect when inserted between a pair of candy canes arranged in nested relation. It will also be apparent from the foregoing description that the flexible strip which I employ not only 80 exerts a lateral spreading force with respect to the nested canes within the container, but also causes said canes to be spread longitudinally, thereby positively precluding the presence of longitudinal lost motion within the 85 container. 90

Having thus described my invention what I claim as new and desire to secure by Letters Patent is:

1. Means for packaging candy canes including a container for receiving a pair of canes arranged in nested relation with the top of one adjacent the bottom of the other, and means for insertion between a pair of said nested canes for exerting constant pressure 100 to separate them.

2. Means for packaging candy canes including a container for receiving a pair of canes arranged in nested relation with the top of one adjacent the bottom of the other, and resilient means for insertion between a pair of said nested canes for exerting a constant pressure to separate them, the container being designed to hold said nested canes together sufficiently to keep the resilient separating means under compressive strain. 110

3. In combination with a container for receiving candy canes in nested relation with the tip of one adjacent the crook of another, a cushioning element adapted to be inserted 115 around both ends and within the crooks of said nested canes for separating said canes within the container.

4. In combination with a container for candy canes arranged in nested relation with the tip of one adjacent the crook of another, a folded filler strip adapted to be inserted between said nested canes so as to yieldingly bear against said canes to separate them. 120

5. Means for packaging candy canes including a container for receiving a pair of candy canes arranged in nested relation with the tip of one adjacent the crook of the other, and a cushion-like filler member adapted to be inserted around both ends and within the 130

crooks of said nested canes, one width of the container being substantially equal to the diameter of the candy cane stock, and the other width being such as to cause the container walls to hold the canes close enough together to maintain the cushion-like filler member under compressive strain.

6. In combination with a container for candy canes arranged in nested relation with the tip of one adjacent to the crook of the other, a resilient filler strip which is V-shaped in cross section and which is adapted to assume an S-shape for insertion between said nested canes.
- 10 7. In combination with a container for candy canes arranged in nested relation with the tip of one adjacent the crook of the other, resilient means for insertion between said nested canes to yieldingly bear against said canes to separate them, said resilient means being treated with a waxy substance to prevent the adhesion of the resilient means and said candy canes.
